TELEVISION SYSTEM

Arthur C. Stocker, Haddon Heights, N. J., assignor, by mesne assignments, to Radio Corporation of America, New York, N. Y., a corporation of Delaware

Application October 23, 1934, Serial No. 749,510

7 Claims. (Cl. 250—27)

My invention relates to improvements in television systems.

In one form of television receiving system, a cathode ray tube is utilized to develop an image of the transmitted view. This tube is provided with a fluorescent screen and with means for developing a ray of electrons and directing the ray at the screen. For the purpose of causing the ray to scan the screen, it is deflected simultaneously in the horizontal and vertical directions, in synchronism with the respective corresponding scanning actions at the transmitter. The tube is provided with means for focusing the ray to a relatively small spot on the screen, and is also provided with one or more electrodes whose function is to accelerate the electrons toward the screen so that they strike the latter at a relatively high velocity. In this way, the screen is caused to fluoresce at the particular elemental area thereof at which the ray is directed at any instant, the brilliancy of the spot developed being a function of the intensity of the ray, which is controlled by the incoming picture signals.

In the systems of the character referred to, and particularly those requiring relatively high anode current at high voltages to obtain sufficient light on the screen for projection purposes, the intensity of the cathode ray is sufficient to burn a spot on the fluorescent screen if it is continuously directed at this spot for even a fraction of a second. That is, if, on starting the apparatus, the intensity of the ray becomes nearly normal before the deflecting circuits begin to function to deflect the ray, it will burn and permanently ruin the fluorescent screen. Furthermore, if, in shutting down, the deflecting circuits cease to function before the ray is cut off or at least reduced substantially in intensity, the screen will be damaged. Also, if there is a failure in the power supply, or a failure at some point in the system to render the deflecting circuits ineffective so that the ray is directed continuously at one spot on the screen, the latter will be burnt at this spot.

For the purpose of protecting the fluorescent screens against burning by the cathode ray under the conditions explained, it has been proposed to provide automatic means for cutting off the ray upon failure of the deflecting circuits, or for maintaining the ray at cut-off until the deflecting circuits are functioning properly, in starting up, or for cutting off the ray before the deflecting circuits cease to function, in shutting down. These automatic systems proposed heretofore, however, require the use of complicated switching actions, the use of relays, and, generally, are

unreliable for faithful service over a long period of time.

With the foregoing in mind, it is one of the objects of my invention to provide an improved television system of the character referred to wherein provision is made for protecting the fluorescent screen against burning by automatic means effective to cut off the ray upon loss of deflection, to maintain the ray at cut off until the deflecting circuits begin to function properly in starting up, or to cut off the ray as the reflecting circuits cease to function in shutting down.

Another object of my invention is to provide an improved television system of the character referred to wherein provision is made for cutting off the ray, for the purpose explained, by means which are automatic and also relatively simple in construction and in operating action, and which are reliable in operation.

Other objects and advantages will hereinafter appear.

In accordance with my invention, the bias on the electron gun for cutting off the ray is supplied by a filter circuit having a predetermined time constant of operation. The positive potentials supplied to the anodes of the tube, for accelerating the ray toward the screen, are supplied from a second filter having a time constant of operation substantially greater, that is, longer, than that of the first filter. The arrangement and operating action are such that upon closing the switch to the common power supply, in starting up, the bias on the grid of the electron gun builds up at a substantially higher rate than the first and second anode voltages. In this way, the anode current is reduced to a safe value, at which the screen is not damaged although the deflecting circuits might not be operating. When the deflecting circuits begin to function properly, the bias is reduced automatically so that the ray is then at normal intensity. Upon failure of the deflecting circuits for any reason, the bias is increased automatically to cut off the ray. When the main power switch is opened, such as in shutting down, the bias builds up automatically to cut off the ray, and then decays at a rate substantially lower than the rate of decay of the respective voltages on the first and second anodes, whereby the anode current is kept at a safe value as the deflecting circuits cease to function.

My invention resides in the improved system and method of operation of the character hereinafter described and claimed.

For the purpose of illustrating my invention, an

embodiment thereof is shown in the drawing, wherein:

Figure 1 is a simplified, diagrammatic view of a television receiving system constructed and operating in accordance with my invention; and

Fig. 2 is a graphical view, illustrative of the principle of operation of the system shown in Fig. 1.

In Fig. 1, the reference numeral 10 designates a conventional cathode ray tube provided with a fluorescent screen 12 and an electron gun 14 for developing a cathode ray 16 and directing the same at the screen. The gun is provided with a control grid 18 to which incoming picture signals and horizontal and vertical synchronizing signals are applied by way of a connection 20 from a receiver 22.

A biasing potential is applied to the grid 18 through a grid leak 24 connected to a resistor 26 20 by an adjustable contact 28.

For the purpose of causing the ray 16 to scan the screen 12, a saw-tooth current wave at a relatively high frequency, generated by a circuit designated at 34, is caused to pass through electromagnetic coils 32. Simultaneously with this 25 action, a saw-tooth wave at a relatively low frequency, generated by a circuit designated at 30, is caused to pass through electromagnetic coils 36.

30 The receiver 22 operates to separate the horizontal synchronizing signals from the other incoming signals, and to supply only these by way of a connection 40 to the circuit 34. These signals are effective to drive the circuit 34 and 35 maintain operating action of the same in synchronism with operating action of the corresponding circuit at the transmitting station.

Likewise, the receiver 22 operates to separate the vertical synchronizing signals from the other 40 signals, and to supply only these by way of a connection 38 to the circuit 30. This circuit is driven by the vertical synchronizing signals, and operating action thereof is maintained thereby in synchronism with operating action of the corresponding circuit at the transmitter.

The incoming horizontal and vertical synchronizing signals are of the same polarity as, but are greater in amplitude than the incoming picture signals representative of conditions of shade at 50 the transmitter. Under such conditions, these signals are applied to the grid 18 of the electron gun.

As the ray 16 is caused to scan the screen 12 along horizontal lines from left to right, looking 55 toward the right in Fig. 1, and downward, a horizontal synchronizing signal occurs at the end of each horizontal line, and as the ray begins its return deflection to the left. A vertical synchronizing signal occurs at the end of each frame 60 when the ray is directed at the lower right-hand corner of the screen, looking toward the right in Fig. 1, and as the ray begins its return deflection back to the starting point at the upper left-hand corner of the screen. In this way, a negative 65 potential is applied to the grid 18 sufficient to substantially cut off the ray during return deflection thereof in both the horizontal and vertical directions.

The details of circuits suitable for deflection of 70 the ray, and a detailed explanation of the nature of the picture signals and the horizontal and vertical synchronizing signals, is to be found in the copending application of Arthur W. Vance, Serial No. 544,959, filed June 17, 1931. Since 75 these details form no part of my present invention,

no additional explanation of the same is believed to be necessary.

The tube 10 is provided with a first anode 42 which forms part of the electron gun 14, and with a second anode 44 in the form of a metallic coating on the inside surface of the tube. In operation, a potential positive with respect to the cathode 46 of the electron gun is applied to the anode 42 by a connection 48 from a tap on a resistor 50. A potential, considerably more positive than the potential on the first anode 42, is applied to the second anode 44 by a connection 52 from the resistor 50. Under these conditions, the ray 16 is focused to a relatively small spot on the screen 12. The first anode 42 is effective to accelerate the electrons toward the screen. The anode 44, at the higher positive potential, is effective to further accelerate the electrons toward the screen.

Operating power for the system is obtained from a common alternating current supply connected through a switch 56 to the primary 58 of a transformer 60. A filter 64 is connected across a portion of the secondary winding 62 through a rectifier tube 66, and feeds a load comprising the resistor 26 and a second resistor 68 connected to ground, as represented.

The high voltage winding 62, a rectifier tube 70 and a filter 72 comprise the supply potential for the receiver 22 through a connection 74, and the potential supply for the circuits 30 and 34 through this connection and a connection 76.

The biasing potentials for the various tubes are supplied by a connection 78 from the tap to the transformer winding 62.

The resistor 50 is supplied from a filter 84, rectifier tubes 86 and a secondary winding 88 of the power transformer.

The condensers 80 and 82 of the filter 64 and the resistors 26 and 68 are so proportioned with respect to the condensers 90 and 92 of the filter 84 that on removal of the supply power, the bias voltage at the contact 28 decays more slowly than the voltage at the point 94 which is applied to the first anode 42 and the voltage at the point 96 which is applied to the second anode 44. In other words, the filter 64 and associated parts, for supplying the bias to the electron gun 14 has a time constant of operation, in shutting down, substantially greater than the time constant of operation of the filter 84 and associated parts for supplying the operating potentials to the first anode 42 and the second anode 44.

Also, the condensers 80 and 82, the resistor of the filter 64, and the internal resistance of the rectifier tube 66, are so proportioned with respect to the condensers 90 and 92, the resistor of the filter 84, and the internal resistance of the associated rectifier tubes 86, that upon application of the supply power, in starting up, the bias voltage at the contact 28 builds up more rapidly than the voltages at the points 94 and 96. The filter 64 and associated parts for supplying the bias to the electron gun 14, therefore, have a time constant of operation, in starting up, substantially smaller, that is, shorter, than the time constant of operation of the filter 84 and associated parts for supplying the operating potentials to the first anode 42 and the second anode 44. The reason for this will hereinafter more fully appear.

The plate of a bias detector tube 98 is supplied, through a filter 100 and a connection 102, from the main plate supply from the filter 72. This tube is biased to cut-off through a grid resistor 104 connected by a contact 106 to the resistor 26.

The grid of the tube 98 is coupled to the horizontal deflecting coils 32 through a condenser 108.

The plate of a second bias detector tube 110 is supplied, through a filter 112 and the connection 5 102, from the main plate supply from the filter 72. The tube 110 is biased to cut-off through a grid resistor 114 connected as shown to the contact 106. The grid of the tube 110 is coupled through a condenser 116 to the vertical deflecting 10 coils 36.

The various adjustments and the construction of the tubes 86 and 88 are such that the filament of the tube 86 becomes hot at least as soon as the filaments of the tubes 88. When the switch 56 is closed, therefore, the tube 86 begins to draw current and to operate at least as soon as the tubes 88.

The bias supplied to the grid 18 from the resistor 26, and which is required for cutting-off 20 the ray 16, is always a definite percentage of the voltage on the first anode 42.

All tubes in both deflecting circuits 30 and 34 and in the receiver 22 have their cathodes connected to ground.

25 The operation of the system will now be explained, with reference to Fig. 2, in which the percentage of biasing potential on the grid 18 and the percentage of potential on the second anode 44 are plotted against time. One hundred percent bias on the grid 18 is sufficient to cut off the ray with one hundred percent of the normal operating voltage on the second anode 44.

When the switch 56 is closed in starting, the bias on the grid 18 builds up in a manner represented by the curve 118 in Fig. 2, and at a greater rate than the voltage on the second anode 44, which builds up in a manner represented by the curve 123. During this time, therefore, the tube 98 is cut off. When the horizontal deflecting

40 circuit 30 begins to function effectively at the point 121 in Fig. 2, the alternating current voltage across the deflecting coils 32 is impressed on the grid of the tube 98 to cause it to pass plate current, thereby causing the voltage at the point 45 122 to become substantially less negative with respect to ground. The voltage at the contact 28 therefore becomes substantially less negative with respect to ground whereby the bias on the grid 18 is reduced to the point, represented at 50 123, whereat the intensity of the ray is normal. From this it will be seen that in starting up the screen 12 is protected, since the bias on the grid 18 builds up at a substantially greater rate than the potential on the second anode 44.

55 If there is a failure due, for example, to the burning out of a tube in the deflecting circuit 30, or to the occurrence in this circuit of a short-circuit to ground, or the loss of "B" supply to this circuit, the tube 98 is automatically cut off 60 to cause the voltage at the point 122 to become more negative and, accordingly, the biasing potential at the contact 28 to become substantially more negative to cut off the ray. The bias on the grid 18 then increases, as represented by the 65 curve 126, to the value of one hundred percent bias, whereat the ray is cut off and the screen 12 protected at this time, when the deflecting circuit 30 is ineffective.

When the switch 56 is opened, in shutting 70 down, the deflecting circuit 30 ceases to operate, and the bias on the grid 18 increases to the cut-off value, as just explained, from the point 123 and along the curve 126 to the point 128. The bias on the grid 18 then decreases as represented 75 by the curve 130, at a substantially lower rate

than the decay of the voltage on the second anode 44, as represented by the curve 132. In shutting down, there is therefore always sufficient bias on the grid 18 to keep the intensity of the ray 16 sufficiently low so that the screen 12 is protected 5 against burning as the voltage on the second anode 44 decays.

The operating action with respect to the tube 110 is the same as that just explained in connection with the tube 98. That is, the tube 110, 10 which is responsive to conditions of voltage across the vertical deflecting coils 36, is effective to cause the ray 16 to be cut off upon failure of the circuit 34 to supply the required operating voltage 15 to the coils 36.

From the foregoing it will be seen that I have provided an improved television receiving system embodying a cathode ray tube, in which means are provided for protecting the fluorescent screen against burning by the ray by cutting off 20 the ray in starting until the deflecting circuits began to operate, by cutting off the ray in shutting down, until the operating potentials on the anodes of the cathode ray tube decay to safe 25 values, and by cutting off the ray in the event of failure of deflection during operation.

While I have disclosed my invention in connection with a television receiving system, it will be understood that the same has a much broader aspect, and might be embodied to advantage in 30 a transmitting system having a cathode ray tube for developing the picture signals, or in connection with a cathode ray oscilloscope to protect the screen thereof.

Furthermore, it will be understood that various modifications, within the conception of those skilled in the art, are possible without departing from the spirit of my invention and the scope of the claims.

I claim as my invention:

1. In combination, a tube provided with a screen and with means including an anode and a control electrode for developing a ray of electrons and directing the ray at said screen, means for deflecting said ray, means for supplying a biasing potential to said control electrode to substantially cut off said ray, means for supplying an operating potential to said anode to accelerate the electrons toward said screen, and means common with respect to said third-named and 45 fourth-named means for supplying the same with operating power, said third-named means being characterized by the fact that upon removal of the operating power it has a time constant of operation substantially greater than the time 50 constant of operation of said fourth-named means.

2. In combination, a tube provided with a screen and with means including an anode and a control electrode for developing a ray of electrons and directing the ray at said screen, means for deflecting said ray, means including a first filter circuit for supplying a biasing potential to said control electrode to substantially cut off said ray, means including a second filter circuit for 60 supplying an operating potential to said anode to accelerate the electrons toward said screen, and means common with respect to said filter circuits for supplying the same with operating power, said third-named means and the first 65 filter associated therewith having a time constant of operation substantially greater than the time constant of operation of said fourth-named means and the second filter associated therewith upon removal of the operating power. 70 75

3. In combination, a tube provided with a screen and with means for developing a ray of electrons and directing the ray at said screen, said means including a control electrode, said tube being provided with an anode for accelerating the electrons toward said screen, means for deflecting said ray, means including a combination rectifier-and-filter circuit for supplying an operating potential to said anode, means including a second combination rectifier-and-filter circuit for supplying a biasing potential to said control electrode to substantially cut off said ray, and means common with respect to said circuits for supplying the same with operating power, said fourth-named means upon application of the operating power having a time constant of operation substantially smaller than the time constant of operation of said third-named means.
4. In combination, a tube provided with a screen and with means for developing a ray of electrons and directing the ray at said screen, said means including a control electrode, means for deflecting said ray, a circuit for supplying said deflecting means with a voltage wave, means for supplying said control electrode with a biasing potential, a detector tube connected to said third-named means and biased substantially to cut off thereby, and connecting means between said circuit and the grid circuit of said detector tube whereby the latter is caused to draw current only under conditions whereat said circuit is effective for deflecting said ray.
5. In combination, a tube provided with a screen and with means for developing a ray of electrons and directing the ray at said screen, means for deflecting said ray, means for accelerating the electrons toward said screen and having a given time constant of operation, means for cutting off said ray and having a time constant of operation upon the application of power thereto substantially less than that of said accelerating means, and means controlled by said ray-deflecting means and operable responsive to effective ray-deflecting action of the latter to remove the influence of said fourth-named means whereby the intensity of said ray is caused to

reach a value corresponding substantially to that for normal operation of said tube.

6. In combination, a tube provided with a screen and with means for developing a ray of electrons and directing the ray at said screen, said means including a control electrode, means for deflecting said ray, means for supplying a biasing potential to said control electrode to substantially cut off said ray, means for supplying an operating potential to said tube to accelerate the electrons toward said screen, and means common with respect to said third-named and fourth-named means for supplying the same with operating power, said third-named means being characterized by the fact that upon removal of the operating power it has a time constant of operation substantially greater than the time constant of operation of said fourth-named means while upon application of the operating power said third-named means has a time constant of operation substantially less than the time constant of operation of said fourth-named means.

7. In combination, a tube provided with a screen and with means for developing a ray of electrons and directing the ray at said screen, said means including a control electrode, means for deflecting said ray, means including a first filter circuit for supplying a biasing potential to said control electrode to substantially cut off said ray, means including a second filter circuit for supplying an operating potential to said tube to accelerate the electrons toward said screen, and means common with respect to said filter circuits for supplying the same with operating power, said third-named means and the first filter associated therewith having a time constant of operation substantially greater than the time constant of operation of said fourth-named means and the second filter associated therewith upon removal of the operating power and having a time constant of operation substantially less than the time constant of operation of said fourth-named means and the second filter associated therewith upon application of the operating power.

ARTHUR C. STOCKER.
